ABSTRACT

A novel material size reducing and storage device system comprising of at least one material size reducing unit which is capable of shredding, grinding, cutting or using other similar methods for the purpose of recycling plastic, metal, paper, and other materials; a storage unit; an apparatus that analyzes and detects the type or recyclable; a heating system that facilitates further size reduction of recyclable; a cooling system that maintains cool temperatures for food waste; a computer system having self-monitoring analysis and reporting technology (SMART); and a cleaning system that removes contamination from material so that said material is ready to be upcycled in a recycling facility.

SIZE REDUCTION AND STORAGE DEVICE SYSTEM AND METHOD OF USE

BACKGROUND

1. Field of the Invention

The present invention relates generally to size reduction and storage devices. More specifically, the present invention relates to a novel size reduction and storage device system that can detect material type, reduce said material to predetermined size(s), wash said material to remove contaminants, and store said material to be later transferred to a recycling facility.

2. Description of Related Art

The recycling industry is reeling from the 2018 China announcement that it would no longer receive recyclables with contamination of 0.5% or higher. For China to receive recyclables, the material must be 99.5% pure. Recycling facilities' current processes, along with consumer participation, make it nearly impossible to meet that standard with current contamination rates between 25% and 30%. This high rate greatly increases processing costs.

The problem, from the consumer standpoint, is that recycling is confusing and difficult. This fact is reflected in over 90% of Americans support recycling, yet less than 35% of Americans recycle.

There are seven classifications of recyclable plastics, four classifications of recyclable paper, and thirteen types of recyclable scrap metal. Most recycling centers do not accept plastic bags and only receive Plastic #1—PETE (Polyethylene Terephthalate) and Plastic #2—HDPE (High Density Polyethylene) of recyclable plastics, generally in bottle form only. What is and is not accepted by recycling centers is confusing to many consumers. The natural default for the consumer becomes throwing good recyclables into the trash because it is easier. Additionally, many consumers must go out of the way to turn in their recyclables. This inconvenience often translates into potential recyclables becoming waste in landfills.

Recycling centers have attempted different types of programs to encourage consumers to recycle. Curbside recycling programs are offered in most communities, but due to lack of education, many households think that items like bowling balls, garden hoses and batteries should go into the recycling bins. Although the participation is welcomed, these acts lead to costly fixes and high levels of recycling material contamination.

There has been very little innovation in the collection of recyclables. Some companies have offered corrugated boxes for consumers to fill and mail back at the consumer's expense. These types of services have low participation due to inconvenience and high shipping costs. Another method of attempting to boost involvement is utilizing a single acceptable coupled with a discount incentive program. Although liked by the few who recycled this way, due to the small number of units serving a large geographic area, this method has virtually no traction.

For most consumers and businesses, the current recycling programs, methods, and systems are difficult to participate in. A simpler approach that is in line with normal everyday habits is required to have a successful recycling program.

Accordingly, although great strides have been made in the area of size reduction and storage device systems, many shortcomings remain.

Therefore, a need exists in the field for a novel size reduction and storage device systems capable of recycling all seven classifications of plastics, four classifications of recyclable paper, and multiple types of recyclable metals by reducing the material size of the recyclable and thus allowing uncontaminated material to be stored in less space. A further need exists for a size reduction and storage device that incorporates SMART (Self-Monitoring Analysis and Reporting Technology) technology to create an intuitive, proactive communication module within the recycling device to increase user usage and buy-in. Finally, there is also a need for a size reduction and storage device to be simple to use and seamlessly integrated into our everyday lifestyle.

15

BRIEF SUMMARY OF THE INVENTION

The present invention comprises a novel size reduction and storage device system generally consisting of at least one material size reducing unit which is capable of shredding, grinding, cutting or use other similar methods for the purpose of recycling plastic, metal, paper, glass, and other materials. A storage unit, an apparatus that analyzes and detects plastic types, a computer system, and a cleaning system are part of the preferred embodiments.

Accordingly, in one embodiment, the present disclosure provides for the methodology of a novel size reduction and storage device system, wherein an item is placed within the size reduction and storage device to be shredded and later transferred to a recycling facility. For example, the process may involve the following steps:

- a) scanning the item to verify the type of recyclable;
- b) shredding the item into smaller pieces;
- c) moving the shredded item into an assigned storage chamber;
- d) washing the shredded item to remove any contamination;
- e) moving the washed shredded item into the heating system;
- f) prompting the user to transfer the shredded contents of the storage chamber or the heating system into a shipping package;
- 45 g) the user scanning the shipping package to track the transportation history of the shredded contents and to see what the shredded contents are upcycled into; and
- h) the user mailing or using curbside service to transport the shredded contents within the shipping package to a recycling facility.

In one embodiment, the present disclosure provides for the methodology of a novel size reduction and storage device system, wherein an item is placed within the size reduction and storage device to be shredded and later transferred to a recycling facility. For example, the process may involve the following steps:

- 55 a) scanning the item to verify the type of recyclable;
- b) depositing the item into a corresponding receiving port;
- c) closing and locking the corresponding receiving port;
- d) shredding the item into smaller pieces;
- e) moving the shredded item into a holding tank;
- f) washing the shredded item to remove any contamination within the holding tank;
- 60 g) prompting the user to transfer the washed shredded item from the holding tank into a tanker truck;
- h) transporting the washed shredded item to a recycling facility; and
- i) communicating with the user of the status of the washed shredded item.

These and other aspects of the invention will be apparent upon reference to the following detailed description.

DESCRIPTION OF THE DRAWINGS

The novel features believed characteristic of the embodiments of the present application are set forth in the appended claims. However, the embodiments themselves, as well as a preferred mode of use, and further objectives and advantages thereof, will best be understood by reference to the following detailed description when read in conjunction with the accompanying drawings, wherein:

FIG. 1 is a perspective view of a size reduction and storage device system in accordance with a preferred embodiment of the present invention;

FIG. 2A is a perspective inside view of a size reduction and storage device system in accordance with a preferred embodiment of the present invention;

FIG. 2B is a schematic side profile inside view of a size reduction and storage device system in accordance with a preferred embodiment of the present invention;

FIG. 3A is a schematic of a size reduction unit for flexible material in accordance with the present application;

FIG. 3B is a disassembled view of a size reduction unit for flexible material in accordance with the present application, illustrating a set of rollers;

FIG. 3C is a disassembled view of a size reduction unit for flexible material in accordance with the present application, illustrating a male cutting roller;

FIG. 3D is a disassembled view of a size reduction unit for flexible material in accordance with the present application, illustrating a female cutting roller;

FIG. 4 is a schematic of a size reduction unit for non-flexible material in accordance with a preferred embodiment of the present invention;

FIG. 5 is a schematic of a storage unit and several components in accordance with a preferred embodiment of the present invention;

FIG. 6 is a schematic of a heating system in accordance with a preferred embodiment of the present invention;

FIG. 7A is a schematic of a cleaning system in accordance with a preferred embodiment of the present invention;

FIG. 7B is a disassembled cross-sectional view of the cleaning system of FIG. 7A in accordance with the present application;

FIG. 7C is a schematic of a spray wand of the cleaning system in FIG. 7A in accordance with the present application;

FIG. 8 is a block diagram of a size reduction and storage device system in accordance with an embodiment, illustrating an example of a computer system within which instructions for causing a machine to perform any one or more of the methodologies discussed herein may be executed;

FIG. 9 is a flowchart of the method of use of the systems of the present application;

FIG. 10 is a perspective inside view of an alternative size reduction and storage device system in accordance with a preferred embodiment of the present invention;

FIG. 11 is a schematic view of the system in FIG. 10 in accordance with a preferred embodiment of the present application;

FIG. 12 is a schematic view of the size reduction blades of the system in FIG. 10 in accordance with a preferred embodiment of the present application;

FIG. 13 is a schematic of an alternative heating system in accordance with an embodiment of the present invention; and

FIG. 14 is a schematic of a cooling system in accordance with a preferred embodiment of the present invention.

While the system and method of use of the present application is susceptible to various modifications and alternative forms, specific embodiments thereof have been shown by way of example in the drawings and are herein described in detail. It should be understood, however, that the description herein of specific embodiments is not intended to limit the invention to the particular embodiment disclosed, but on the contrary, the intention is to cover all modifications, equivalents, and alternatives falling within the spirit and scope of the present application as defined by the appended claims.

DETAILED DESCRIPTION OF THE PREFERRED EMBODIMENT

Illustrative embodiments of the system and method of use of the present application are provided below. It will of course be appreciated that in the development of any actual embodiment, numerous implementation-specific decisions will be made to achieve the developer's specific goals, such as compliance with system-related and business-related constraints, which will vary from one implementation to another. Moreover, it will be appreciated that such a development effort might be complex and time-consuming, but would nevertheless be a routine undertaking for those of ordinary skill in the art having the benefit of this disclosure.

The terminology used herein is for the purpose of describing particular embodiments only and is not intended to be limiting of the invention. As used herein, the term "and/or" includes any and all combinations of one or more of the associated listed items. As used herein, the singular forms "a," "and," and "the" are intended to be included in the plural forms as well as the singular forms, unless the context clearly indicates otherwise. It will be further understood that the terms "comprises" and/or "comprising," when used in this specification, specifically the presence of stated features, steps, operations, elements, and/or components, but do not preclude the presence or addition of one or more other features, steps, operations, elements, components, and/or groups thereof.

Unless otherwise defined, all terms (including technical and scientific terms) used herein have the same meaning as commonly understood by one having ordinary skill in the art to which this invention belongs. It will be further understood that terms, such as those defined in commonly used dictionaries, should be interpreted as having a meaning that is consistent with their meaning in the context of the relevant art and the present disclosure and will not be interpreted in an idealized or overly formal sense unless expressly so defined herein.

In describing the invention, it will be understood that a number of techniques and steps are disclosed. Each of these has individual benefit and each can also be used in conjunction with one or more, or in some cases all, of the other disclosed techniques. Accordingly, for the sake of clarity, this description will refrain from repeating every possible combination of the individual steps in an unnecessary fashion. Nevertheless, the specification and claims should be read with the understanding that such combinations are clearly within the scope of the invention and the claims.

The system and method of use in accordance with the present application overcomes one or more of the above-discussed problems commonly associated with conventional size reduction and storage device systems. Specifically, the system of the present invention incentives consumers to

recycle at their convenience as well as preps items to be recyclable ready in downstream recycling facilities. These and other unique features of the system and method of use are discussed below and illustrated in the accompanying drawings.

The system and method of use will be understood, both as to its structure and operation, from the accompanying drawings, taken in conjunction with the accompanying description. Several embodiments of the system are presented herein. It should be understood that various components, parts, and features of the different embodiments may be combined together and/or interchanged with one another, all of which are within the scope of the present application, even though not all variations and particular embodiments are shown in the drawings. It should also be understood that the mixing and matching of features, elements, and/or functions between various embodiments is expressly contemplated herein so that one of ordinary skill in the art would appreciate from this disclosure that the features, elements, and/or functions of one embodiment may be incorporated into another embodiment as appropriate, unless described otherwise.

The preferred embodiment herein described is not intended to be exhaustive or to limit the invention to the precise form disclosed. It is chosen and described to explain the principles of the invention and its application and practical use to enable others skilled in the art to follow its teachings.

Referring now to the drawings wherein like reference characters identify corresponding or similar elements throughout the several views, FIG. 1 depicts a perspective view of a size reduction and storage device system 101 in accordance with a preferred embodiment of the present invention. It will be appreciated that system 101 overcomes one or more of the above-listed problems commonly associated with conventional size reduction and storage device systems.

In the contemplated embodiment, system 101 includes a housing unit 103 incorporating an access door 105, one or more display units 107 (e.g., a liquid crystal display (LCD) cathode ray tube (CRT), etc.), a scanner 109, an entryway of a size reduction unit for flexible material 111, one or more light emitting diodes (LEDs) 113, a storage drawer 115, a second access door 117, and the front portion of a printer 119. In a preferred embodiment, the access door 105, the one or more display units 107, the scanner 109, the size reduction unit for flexible material 111, the one or more LEDs 113, for instance LED 113a and LED 113b, the storage drawer 115, and the second access door 117 are oriented in the front portion of the housing unit 103a.

The display unit 107 broadcasts a textual message, a graphical message, or a combination thereof to communicate with a user as well as receiving input information from the user. It is contemplated and will be appreciated that the display unit 107 may incorporate touch screen technology, a microphone and a speaker to further facilitate communication with the user.

It is also contemplated and will be appreciated that the size reduction unit for flexible material 111 takes in and shreds items including, but not limited to, clear food packaging, produce bags, garbage bags, shrink wrap, plastic wrap, and film wrap.

It is also contemplated and will be appreciated that the access door 105 and the second access door 117 incorporates manual means, automation technology, or a combination thereof to facilitate opening and closing. The second access

door 117 allows for easier access to the interior components of system 101 which are discussed below.

It is further contemplated and will be appreciated that the one or more LEDs 113 is exemplary, and it should be understood that other light emitting sources, such as, but not limited to, incandescent, plasma and fiber-optic sources may be utilized. It is likewise contemplated and will be appreciated that the one or more LEDs 113 may emit one or more identical colors, different colors, or a combination thereof.

10 For example, the one or more LEDs may emit a green color to inform the user that the system is ready to take in an item to be shredded. In another example, the one or more LEDs may emit a yellow color to inform the user that the access door is not properly closed.

15 Referring now to FIGS. 2A and 2B, with reference to FIG. 1, a perspective inside view of a size reduction and storage device system 201 and a schematic side profile inside view of a size reduction and storage device system 201 in accordance with a preferred embodiment of the present invention are shown, respectfully. In the contemplated embodiment, system 201 includes a safety locking mechanism 203 as a means to prevent the access door 105 from opening during use. Additionally, system 201 includes a hinge 211 in communication with the access door 105 and the housing unit 103 to facilitate the opening and closing of the access door 105. System 201 also incorporates one or more drawer glides 209 to facilitate the opening and closing of the storage drawer 115. System 201 also includes a computer system 207 (further discussed below and shown in FIG. 10), a storage unit 223 (further discussed below and shown in FIG. 5), a cleaning system 601 (further discussed below and shown in FIGS. 7A, 7B and 7C), and a heating system 515 (further discussed below and shown in FIGS. 5 and 6).

20 Moreover, system 201 includes an electric motor 215 in communication with a gear reduction box 217. System 201 incorporates at least one size reduction unit for nonflexible material 205 in communication with the gear reduction box 217. The electric motor 215 powers the gear reduction box 217 to drive the size reduction unit for nonflexible material 205 to shred nonflexible material (not shown) to a predetermined size.

25 System 201 also includes an apparatus 213 to detect and analyze the type of plastic a nonflexible material (not shown) is. It is contemplated and will be appreciated that the apparatus 213 comprises of suitable material capable of ensuring that the correct identification of each plastic type is assigned to each nonflexible material. For example, when a user places a nonflexible material (e.g., a milk container) inside the access door 105, the apparatus 213 may scan the nonflexible material and categorize the nonflexible material as Plastic #2.

30 System 201 also incorporates a large chute 219, small chute 221, and a storage unit 223. The large chute 219 is in communication with the size reduction unit for nonflexible material 105 and the storage unit 223. Likewise, the small chute 221 is in communication with size reduction unit for flexible material 111 and the storage unit 223. The storage unit 223 is divided into one or more storage chambers (not shown, see FIG. 5). During use, the large chute 219 transfers shredded nonflexible material (not shown) from the size reduction unit for nonflexible material 205, through the storage unit 223 and into an assigned storage chamber 505 (not shown, see FIG. 5). Likewise, during use, the small chute 221 transfers shredded flexible material (not shown) from the size reduction unit for flexible material 111, through the storage unit 223 and into an assigned storage chamber 505 (not shown, see FIG. 5).

System 201 further includes the printer 119 in communication with the computer system 207. The computer system 207 generates serial lot tracking and other tracking type numbers upon which the printer 119 will print the respected serial lot tracking and other tracking type numbers onto a shipping label. Examples of the printer 119 include, but are not limited to, thermal printers, single-function inkjet printers, multi-function inkjet printers, photo inkjet printers, ink tank printers, monochrome laser printers, color laser printers, LED printers, dot matrix printers, and the like.

Referring now to FIGS. 3A through 3D, various embodiments of the size reduction unit for flexible material are shown. Specifically, FIG. 3A, with references to FIGS. 1, 2A, and 2B, presents a schematic of a size reduction unit for flexible material 301. As shown, a housing unit 303 is in communication with the LED 113a and the entryway of the size reduction unit for flexible material 111. The housing unit 303 encases at least one series of large rollers 305 containing at least one roller axle 319, at least one male cutting roller 307, and at least one female cutting roller 309.

As shown, a texturized belt 315 surrounds one or more individual large rollers, for instance large rollers 305a and 305b, containing one or more belt position rollers 325. Additionally, the series of large rollers 305 are oriented on one or more spindles 311 and are powered by a roller motor 313. During use, the roller motor 313 turns a roller belt 317 which moves flexible material (not shown) (e.g., clear food packaging) on the texturized belt 315 to the male cutting roller 307 and the female cutting roller 309.

As shown in FIGS. 3C and 3D, the male cutting roller 307 comprises of one or more cutting blades 321 whereas the female cutting roller 309 comprises of one or more slotted surfaces 323. During use, as the texturized belt 315 transfers flexible material (not shown) to the male cutting roller 307 and the female cutting roller 309, the flexible material is cut to a predetermined size and is dropped into the small chute 221 to be deposited into its assigned storage chamber 505 (not shown, see FIG. 5).

It is contemplated and will be appreciated that the roller axle 319 may be turned by the roller motor 313, the roller belt 317, or any suitable device to achieve the same rotating results.

Referring now to FIG. 4, a schematic of a size reduction unit for nonflexible material 205 is shown. In one embodiment, the size reduction unit for nonflexible material 205 comprises of a shredding house 401 encasing one or more shredding shafts 403, one or more shredding bearings 405, one or more shredding fixed knives 407, and one or more shredding mobile knives 409. The size reduction unit for nonflexible material 205 also incorporates a plunge 411 which supported by one or more pillars and is oriented above the shredding house 401. A series of one or more cables 415 are in communication with the plunge and the access door 105 to facilitate the raising and lowering of the plunge 411 away and toward the shredding house 401, respectfully.

It is contemplated and will be appreciated that the size reduction unit for nonflexible material 205 may be a shredder, grinder, or other similar device suitable to cut, slice, shred, grate, grind, or a combination thereof nonflexible material into predetermined sizes.

It is also contemplated and will be appreciated that the shredding fixed knives 407 and the shredding mobile knives 409 may include any suitable shape to cut the nonflexible material into predetermined sizes.

It is further contemplated and will be appreciated that the size reduction unit for nonflexible material 205 may include

a plunge 411 to facilitate the cutting process of the nonflexible material into predetermined sizes.

FIG. 5, with references to FIGS. 1, 2A and 2B, presents a schematic of a storage unit and several components 501 in accordance with a preferred embodiment of the present invention. As shown, the schematic 501 includes at least one storage unit 223, a storage motor 503, a plurality of storage chambers 505, one or more dividers 507, and a heating system 515. The dividers 507 section the storage unit 223 into the plurality of storage chambers 505. The storage unit 223 and the storage motor 503 are oriented within the storage drawer 115 with a handle 509 to allow a user to open and close the storage drawer 115. The storage drawer 115 also includes a plurality of rollers 513 to facilitate opening and closing. A plurality of hardware 511 secures the drawer glides 209 to the housing unit 103 in which allows the storage drawer 115 to travel on the plurality of rollers 513.

During use, the storage motor 503 rotates the storage unit 223 to allow an assigned storage chamber 505 to receive a specific material (not shown) from the small chute 221 or from the large chute 219 after the material has been reduced in size.

As discussed above, the heating system 515 may utilize heating methods including, but not limited to, fuel-based, electricity-based, gas-based, and steam-based to further reduce the size of material (not shown).

It is contemplated and will be appreciated that the storage motor 503 is in communication with the computer system 207.

FIG. 6 presents a schematic of the heating system in accordance with a preferred embodiment of the present invention. The heating system 515 comprises of a container 603 with a lid 601. The container 603 incorporates an insulated layer 605, a heat layer 607, and a removable inner layer 609.

It is contemplated and will be appreciated that the heating system 515 facilitates to further reduce the size of flexible material, nonflexible material, or both by utilizing methods that are, but not limited to, fuel-based, electricity-based, gas-based, and steam-based.

It is also contemplated and will be appreciated that the insulated layer 605 may include material such as rock wool, slag wool cellulose, glass wool, polystyrene, double walled paper, foam insulation, or other suitable material.

It is likewise contemplated and will be appreciated that the heat layer 607 may include material such as metal heating elements, positive temperature coefficient (PCT) heating elements, composite heating elements, and the like.

It is further contemplated and will be appreciated that the inner layer 609 comprises of crucible material suitable to hold shredded material (not shown) and subject said shredded material to high temperatures.

FIGS. 7A, 7B, and 7C, with reference to FIGS. 1 through 5, depict various embodiments of a cleaning system 701 in accordance with the present application. The cleaning system 701 includes a reservoir 703, a heating element 707, one or more hoses 709, one or more direction control valves 723, a drip pan 713, and a waste reservoir 705.

The reservoir 703 houses a cleaning agent 715 which is used to remove contaminants (not shown) from shredded material (not shown). The hose, for instance hose 709a, bridges the reservoir 703 and an assigned storage chamber, for instance storage chamber 505a. Each assigned storage chamber 505 includes a screen 711 and a spray wand 717 comprising of a plurality of spray heads 725. A direction control valve 723 bridges the hose 709 and the spray wand 717. The screen 711 holds shredded material while allowing

the cleaning agent 715 and contaminates to drip onto the drip pan 711. The plurality of spray heads 725 release the cleaning agent 715 into the storage chamber 505 as the spray wand 717 rotates.

During use, the heating element 707 heats up the cleaning agent 715 inside the reservoir 703 before the cleaning agent 715 is released from the reservoir 703 and into the hose 709. The hose, for instance 709a, transfers the cleaning agent 715 from the reservoir 703 and into the spray wand 717 of an assigned storage chamber, for instance storage chamber 505a, as depicted by directional arrows. As the spray wand 717 rotates within the storage chamber 505a, the direction control valve 723 becomes exposed, allowing the cleaning agent to flow through the spray wand 717 and out through the plurality of spray heads 725. A hose, for instance 709b, transfers mixture of cleaning agent 715 and contaminants from the drip pan 713 and into the waste reservoir 705.

It is contemplated and will be appreciated that the cleaning system 701 may include a lid 719 on each storage chamber 505. It is also contemplated and will be appreciated that the cleaning system 701 may incorporate a condensation tube 721 to transfer condensation into the drip pan 713.

It is further contemplated and will be appreciated that the cleaning system 701 is in communication with the computer system 207.

It is also contemplated and will be appreciated that the cleaning agent 715 may be water, surfactants (e.g., detergent), or any other substance or a combination of substances suitable to achieve cleaning results.

It is likewise contemplated and will be appreciated that the heating element 707 may be any device suitable to convert electrical energy into heat to achieve heating effects of the cleaning agent 715.

It is further contemplated and will be appreciated that the spray head 725 may release the cleaning agent 715 in a pulse-like manner, as vapor, or any suitable fashion to allow adequate removal of contamination from the shredded material.

FIG. 8 presents a block diagram of an embodiment of the size reduction and storage device system, illustrating a non-limiting example of a computer system 801 within which instructions for causing the machine to perform any one or more of the methodologies discussed herein may be executed. In alternative embodiments, the machine operates as a standalone device or may be connected (e.g., networked) to other machines. In a networked deployment, the machine may operate in the capacity of a server or a client machine in a server-client network environment, or as a peer machine in a peer-to-peer (or distributed) network environment. The machine may also be a personal computer (PC), a portable computer, a desktop computer, a tablet (PC), a set-top box (STB), system-on-a-chip (SoC), a personal digital assistant (PDA), cellular telephone, a web appliance, a network router, switch or bridge, or any machine capable of executing instructions (sequential or otherwise) that specify actions to be taken by that machine. Further, while only a single machine is illustrated, the term "machine" shall also be taken to include any collection of machines that individually or jointly execute a set (or multiple sets) of instructions to perform any one or more of the methodologies discussed herein.

In the contemplated embodiment, system 801 includes at least one processor 803 (e.g., central processing unit (CPU), system-on-a-chip (SoC), etc.) with or without instructions 805, a memory 807 with or without instructions 805 and with a self-monitoring analysis and reporting technology (SMART) system 809, an input/output (I/O) interface 811,

and a network interface device 813, which communicate with each other via a bus 817 (e.g., extended industry standard architecture (EISA), conventional peripheral component interconnect (PCI), universal serial bus (USB), processor FireWire, NuBus, etc.). Instructions 805 may reside, completely or at least partially, within the hardware processor 803 and/or memory 807 during execution thereof by system 801. Instructions 805 may include directions for storing instructions, performing one or more functions, and the like.

System 801 also includes a network interface device 813 which facilitates communication with between the computer system 801 and other computing systems (not shown in FIG. 8) via one or more networks 815. Other computing systems, for example, may include conventional computing devices as described above, internet connected devices/systems, or an external storage such as a server, or a cloud computing system.

It is contemplated and will be appreciated that system 801 may include one or more processors, one or more memory units, and one or more I/O interfaces.

It is also contemplated and will be appreciated that memory 807 may include any computer-readable medium or computer program product known in the art including, for example, volatile memory, such as static random access memory (SRAM) and dynamic random access memory (DRAM), and/or non-volatile memory, such as read-only memory (ROM), erasable programmable ROM, flash memories, hard disk drives (HDDs), solid-state drives (SSDs), embedded MultiMediaCards (eMMC), optical disks, compact disks (CDs), digital versatile disc or digital video disc (DVDs) and magnetic tapes. The memory 807 may further include one or more module (not shown in FIG. 8) to perform the methodologies described herein.

It is further contemplated and will be appreciated that the SMART system 809 may detect and report one or more indicators of system 801 reliability. For example, the SMART system 809 may detect that the storage unit 223 is reaching maximum capacity and alters the user so that he or she may take appropriate action.

It is also contemplated and will be appreciated that network 813 may be a wireless network, a wired network, or a combination thereof. Network 813 may also be an individual network or a collection of many such individual networks, interconnected with each other and functioning as a single large network, e.g., the Internet or an intranet. Network 813 may be implemented as one of the different types of networks, such as intranet, local area network (LAN), wide area network (WAN), the internet, near field communication (NFC), and such. Network 813 may either be a dedicated network or a shared network, which represents an association of the different types of networks that use a variety of protocols. Further, network 813 may include network devices, such as network switches, hubs, routers, host bus adapters (HBAs), for providing a communication link between system 101 and other connected devices and/or systems.

It is also contemplated and will be appreciated that the I/O interface 815 may include a variety of software and hardware interfaces (e.g., a web interface, a graphical user interface, and the like). The I/O interface 815 may allow system 801 to interact with a user directly or through the user devices. Further, the I/O interface 815 may enable system 801 to communicate with other computing devices, such as web servers and external data servers (not shown in FIG. 8), or cloud computing systems.

11

It is likewise contemplated and will be appreciated that the I/O interface **815** can facilitate multiple communications within a wide variety of networks and protocol types, including wired networks, for example, LAN, cable, etc., and wireless networks, such as WLAN, cellular, or satellite. The I/O interface **815** may also include one or more ports for connecting a number of devices to one another or to another server.

Referring now to FIG. 9, a flowchart of the method of use **901** of the systems of the present application is shown. The method **901** initiates with step **903** of scanning an item to verify the type of recyclable. The method **901** also includes step **905** of shredding the item into smaller pieces via the size reduction unit for flexible material or the size reduction unit for nonflexible material. The method **901** then includes step **907** of moving the shredded item into an assigned storage chamber. The method **901** also includes step **909** of washing the shredded item to remove any contamination. The method **901** further includes step **911** of moving the washed shredded item into the heating system. The method **901** then includes a step **913** of prompting the user to transfer the shredded contents of the storage chamber into a shipping package. The method **901** then includes step **915** of the user scanning the shipping package to track the transportation history of the shredded contents and to see what the shredded contents are upcycled into. Furthermore, the method **901** includes step **917** of the user mailing or using curbside service to transport the shredded contents within the shipping package to a recycling facility.

It is contemplated and will be appreciated that method **901** may utilize the computer system **207** to accomplish any of the methodologies described herein.

It is also contemplated and will be appreciated that step **903** may take place using scanner **109**, apparatus **213** or **35** both.

It is likewise contemplated and will be appreciated that step **913** may include the printer **119** printing out shipping labels for the user to utilize in steps **915** and **917**.

FIGS. **10,11**, and **12** depict various embodiments of an alternative size reduction and storage system **1001** in accordance with the present application. System **1001** includes a plunge **1003** and a reduction blade unit **1005**. The plunge **1003** rests on top of the storage chamber **505** and a plurality of springs **1105** hold the storage chamber **505** against a grid **1107** creating a watertight seal. The reduction blade unit **1005** includes a base **1203** which holds one or more blades **1205**.

The reduction blade unit **1005** descends into the storage chamber **505** and the one or more blades **1205** rotate within the storage chamber **505** to further reduce the size of material (not shown) as indicated by directional arrows. As the plunge **1003** pushes down into the storage chamber **505**, the plurality of springs **1105** expand breaking the watertight seal as indicated by directional arrows. When the plunge **1003** presses into the storage chamber **505**, the fluid (not shown) is released out through the drain opening **1103**.

Referring now to FIG. 13, a schematic of an alternative heating system **1301** is shown. The alternative heating system **1301** comprises of a heat layer **1303** and an insulated layer **1305** which reside within the structure of the plunge **1003** and the storage chamber **505**. The alternative heating system **1301** also includes a removable liner **1307** which rests within the cavity of the storage chamber **505**. The removable liner **1407** allows for easy cleaning. It should be appreciated that system **1301** allows for further reduction of the size of material such as paper and plastic.

12

Referring now to FIG. **14**, a schematic of a cooling system **1401** is shown. The cooling system comprises of a cooling layer **1403** and an insulated layer **1405** which reside within the structure of the plunge **1003** and the storage chamber **505**. The cooling system **1401** also includes a removable liner **1307** which rests within the cavity of the storage chamber **505**. The removable liner **1407** allows for easy cleaning. It should be appreciated that system **1401** allows for further reduction of the size of material such as food scraps and compost.

The particular embodiments disclosed above are illustrative only, as the embodiments may be modified and practiced in different but equivalent manners apparent to those skilled in the art having the benefit of the teachings herein. It is therefore evident that the particular embodiments disclosed above may be altered or modified, and all such variations are considered within the scope and spirit of the application. Accordingly, the protection sought herein is as set forth in the description. Although the present embodiments are shown above, they are not limited to just these embodiments, but are amenable to various changes and modifications without departing from the spirit thereof.

What is claimed is:

1. A material size reducing and storage device system for facilitating recycling, comprising:
a device, the device having:
a housing unit extending from a front to a back, from a first side to a second side, and from a top to a bottom, thereby forming an interior area;
an access door on the housing unit to provide access to the interior area;
a locking mechanism engaged with the access door to prevent the access door from opening into the housing unit;
a display unit secured to the housing unit and accessible from the front of the housing unit, the display unit to provide information for a user;
a scanner secured within the interior area of the housing unit;
an electric motor disposed within the housing unit;
a gear reduction box disposed within the housing unit;
a size reduction unit for flexible material accessible from the front of the housing unit and extending into the housing unit;
a size reduction unit for nonflexible material accessible from the front of the housing unit and extending into the housing unit, the size reduction unit for nonflexible material is configured to be driven by the gear reduction box, powered by the electric motor, to shred nonflexible material;
a storage door disposed within the housing unit and configured to open and close from the housing unit to enter into a storage unit;
a cleaning system secured to the housing;
a heating system disposed within the housing unit and within the storage unit to receive nonflexible material and flexible material from the size reduction unit for flexible material and the size reduction unit for nonflexible material; and
a computer system secured within the interior of the housing unit and to provide for operation of components of the device;
one or more chutes extending from the reduction unit for flexible material and the reduction unit for nonflexible material and into one or more storage units within the interior area of the housing unit; and

13

- one or more storage drawers extending into the housing unit to provide access to the one or more storage units;
- wherein the display unit communicates to the user and receives input from the user;
- wherein the scanner analyzes and detects recycling material type from flexible and non-flexible material that are inserted into the housing unit; and
- wherein the heating system facilitates further size reduction of flexible material, nonflexible material, or both.
2. The system of claim 1, wherein the size reduction unit for flexible material comprises:
- at least one series of large rollers, the series containing:
- 15 at least one roller axle;
- at least one male cutting roller;
- at least one female cutting roller;
- wherein the male cutting roller having one or more cutting blades;
- 20 wherein the female cutting roller having a slotted surface;
- wherein the female cutting roller receives the one or more cutting blades of the male cutting roller; and
- 25 one or more texturized belts;
- wherein the series of large rollers reduces flexible material to a predetermined size;
- wherein the one or more texturized belts moves the flexible material towards the series of large rollers;
- 30 wherein the reduced flexible material is transferred through the small chute.
3. The system of claim 1, wherein flexible material includes paper, clear food packaging, plastic wrap, saran wrap, or plastic bags.
4. The system of claim 1, wherein the size reduction unit for nonflexible material comprises:
- 35 a housing unit;
- a shaft;
- a bearing;
- one or more fixed knives;
- one or more mobile knives;
- 40 a plunge;
- one or more cables; and
- a large chute;
- wherein the housing unit encases the shaft, bearing, one or 45 more fixed knives, and one or more mobile knives;
- wherein the one or more fixed knives and the one or more mobile knives reduce nonflexible material to a predetermined size;
- wherein the plunge is supported by one or more pillars 50 above the housing unit;
- wherein the plunge raises away and lowers toward the housing unit via one or more cables; and
- wherein the reduced nonflexible material is transferred through the large chute.
5. The system of claim 1, wherein nonflexible material includes hard plastics, metal, and glass.

14

6. The system of claim 1, wherein the cleaning system includes a cleaning agent, the cleaning agent includes, water, surfactants, or a combination thereof.
7. The system of claim 1, wherein the heating system further incorporates heating methods, wherein the heating methods include fuel-based, electricity-based, gas-based, and steam-based.
8. The system of claim 1, wherein the computer system comprises:
- one or more processors;
- one or more memories for storing processor-executable instructions; and
- one or more communication interfaces; and
- wherein the one or more processors communicatively coupled to the one or more memories through the one or more communication interfaces;
- wherein the one or more memories includes self-monitoring analysis and reporting technology;
- wherein upon execution of the processor-executable instructions by the one or more processors, the processor:
- receives input from a user to initiate shredding of a recyclable;
- differentiates the type of material of the recyclable;
- communicates to the user to take appropriate action;
- and
- determines the designation of the shredded recyclable.
9. A method of recycling an item, the method comprising:
- providing the system of claim 1;
- scanning one or more items at a size reduction and storage device to verify the material type;
- inserting the one or more items within the size reduction and storage device;
- scanning the one or more items to reconfirm the material type of the one or more items;
- shredding the one or more items into predetermined sizes;
- heating the one or more items to facilitate further size reduction;
- transferring the shredded one or more items into its assigned storage chamber;
- washing the shredded one or more items to remove contamination;
- 45 displaying a message to remove the shredded one or more items from its assigned storage chamber;
- transferring the shredded one or more items from its assigned storage chamber into a receptacle for curbside service or mailing service to a recycling facility;
- printing a shipping label to be used on the receptacle for curbside service or mailing service to a recycling facility; and
- sharing tracking history information of the one or more shredded items with a user;
- wherein the one or more items include plastic, metal, paper, and glass; and
- wherein the size reduction and storage device contains 50 one or more storage chambers.
